CLAMPING DEVICE

Theodore Melder and Maurice O. Goldsmith,
Boston, Mass.

Application May 12, 1934, Serial No. 725,298

4 Claims. (Cl. 24—251)

Our invention relates to clamping devices generally and especially to clasps for suspenders, garters or other articles which are to support trousers, stockings or other articles.

5 The principal object of our invention is to provide a simple but effective clamping device, which has a very strong grip, which will not get out of order even when used by a careless user, which is adapted to grip articles of different thicknesses, 10 which will be inexpensive to manufacture, which will not bend out of shape, and which will be very durable.

Other objects will be pointed out below.

A feature of our invention is a slide which is 15 movable to close the clamping jaws.

Another feature is a special form of a slide member.

Other features will be pointed out below.

In the drawing

20 Figure 1 is a longitudinal section of a clasp embodying our invention and shown in open position;

Figure 2 is a similar section, on a larger scale, with the clasp closed;

25 Figures 3 and 4 are, respectively, a plan, and side elevation, of one of the jaw members;

Figures 5 and 6 are, respectively, a side elevation and a bottom plan, of the other jaw member;

30 Figures 7 and 8 are, respectively, a plan and a side elevation, of the slide member;

Figure 9 is an elevation of the spring member;

Figure 10 is an elevation of the pin; and

Figure 11 is a section on line 11—11 of Figure 2.

The lower jaw member has a flat base portion 1, preferably of metal, and, integral therewith, side flanges 2 and 3 and end flange 4, the side flanges being upwardly extended at 5 and 6, these extensions being perforated at 7 and 8. The end flange 4 is extended upwardly at 9 to form a clasp jaw.

40 The upper jaw member has a flat base portion 10, preferably of metal, and, integral therewith, side flanges 11 and 12 and end flange 13, the side flanges 11 and 12 being downwardly extended at 14 and 15, these extensions being perforated at 16 and 17 to register with the perforations 7 and 8. The end flange 13 is extended downwardly at 18 to form the other clasp jaw. The upper jaw member is bevelled at each side at 19 for a purpose described below.

45 A pin 20 passes through perforations 7, 8, 16 and 17 and may be headed over at its ends and acts to hold the two jaw members in pivoted relation, the flanges 11 and 12 being just inside of flanges 2 and 3.

5 A spring is coiled about pin 20 and has one leg 21 bearing against the bottom of the upper jaw member and has leg 22 bearing against the top of the lower jaw member, these legs normally tending to separate the jaw ends of the jaw members.

The slide element, shown in Figures 7 and 8, is preferably of metal, and has a body portion 23 and an integral loop portion 24 to receive a portion 25 of a suspender or other supporting article. Integral also with body portion 23 are two upwardly extending cam fingers 26 and 27 spaced apart to permit the coiled spring to be put in place. Each cam finger has an upwardly extending face 28 and a downwardly extending 15 face 29, the latter being spaced from body portion 23, and the two fingers having the function of springs. The two faces 28 and 29 meet at the point 30.

The transverse dimension of the body 23 is 20 such as to make a snug sliding fit between flanges 2 and 3 of the lower jaw member, and the transverse dimension across the fingers and the space between them is such as to permit fitting within the flanges 11 and 12.

25 When the parts are assembled they appear as in Figures 1 and 2.

In Fig. 1 the clamping jaws are shown in the open position, being so held by the spring 21—22. The beveled portions 19, of the side flanges of 30 member 10, permit ample opening of said jaws.

In Fig. 2 the clamping jaws are shown closed. By moving the slide or locking member to the right from the position shown in Fig. 1, to the position shown in Fig. 2, the clamping jaws are 35 closed or brought into clamping position. By moving the locking member to the left from the position shown in Fig. 2 to the position shown in Fig. 1, the jaws are permitted to open in response to the action of the spring 21—22.

40 It will be understood that one spring finger might very well be used but I have shown two spaced apart as a convenience in putting the spring 21, 22 in position.

45 The ends of portions 29 are spaced from body portion 23 not only to gain the spring function referred to but also to permit the right hand portions of the jaw members to come closer together without bending of the left hand portions, which bending might occur if trousers or other material of extraordinary thickness were inserted.

50 It is to be noted that the locking member comprises the part 23, slidable on the inner face of the jaw member 1, and also the resilient or spring extensions or fingers 26 and 27, inclined upwardly 55

from and backwardly over the said part 23, and then inclined downwardly but terminating short of the part 23, to form a resilient cam with the apex 30.

5. This apex 30 is adapted to engage the inner face of the upper jaw member 10, and is adapted to be reciprocated to and from approximate vertical alinement with the pivot center. By "vertical alinement", is meant the position on the broken line *a* in Fig. 1, when the body 1 of the clasp is in horizontal position. The shape and dimension of the cam formation are such that when the locking member is moved to the right to bring the apex 30 to the position shown in Fig. 2, the cam formation 10 is put under tension, so that said tension reacts to force the gripping ends 9 and 18, into effective clamping engagement with a resilient or yielding spring pressure. It follows that, in accordance with this arrangement, the resilient action 15 of the cam serves automatically to lock the clamping ends in effective clamping engagement with fabrics varying in thickness.

What we claim is:

1. A device of the character described comprising a pair of clamping jaw members pivoted together intermediate their two ends, a locking member having a part slideable upon the inner surface of one jaw member and having a resilient cam formation with an apex for slidably engaging 25 the inner surface of the other jaw member, said locking member adapted to be reciprocated to move said apex to and from approximate vertical alinement with the pivot center, so that when moved in direction away from said alinement toward the rear end of the jaw member, the said 30 jaw members are brought into clamping position under resilient pressure.

2. A device of the character described, comprising a pair of clamping jaw members pivoted together intermediate their two ends, a locking member having a part slideable upon the inner 40 face of one jaw member and having an extension

inclined upwardly from and backwardly over said first part and then downwardly to form an apex for engaging the inner face of the other jaw member, said locking member adapted to be reciprocated to and from a position in which the clamping ends of said jaw members are forced into and held in clamping position, and to and from a position in which the separation of said clamping ends is permitted.

3. A device of the character described, comprising a pair of clamping jaw members pivoted together intermediate their two ends, a locking member having a part slideable upon the inner face of one jaw member and having an extension inclined upwardly from and backwardly over the 10 said first part and then downwardly but terminating short of said first part, said formation providing an apex for engaging the inner face of the other jaw member, said locking member adapted to be reciprocated to and from a position 15 in which the clamping ends of said jaw members are forced into and held in clamping position, and to and from a position in which the separation of said clamping ends is permitted.

4. A device of the character described, comprising a pair of clamping jaw members pivoted together intermediate their two ends, a locking member having a part slideable upon the inner face of one jaw member and having parallel extensions inclined upwardly from and backwardly 20 over the said first part and then downwardly, said parallel extensions providing apices for engaging the inner face of the other jaw member, said locking member adapted to be reciprocated to and from a position in which the clamping ends of 25 said jaw members are forced into and held in clamping position, and to and from a position in which the separation of said clamping ends is permitted.
